(57) **CLAIM**

I claim the ornamental design for a tri-lobe planar heel wound dressing, as shown and described.

DESCRIPTION

Planar adhesive wound dressing that becomes non-planar to conform to the shape of the heel.

FIG. 1 is a perspective view of a tri-lobe planar heel wound dressing, showing my new design;

FIG. 2 is a front elevational view thereof;

FIG. 3 is a bottom plan view thereof;

FIG. 4 is a top plan view thereof;

FIG. 5 is a left elevational view thereof;

FIG. 6 is a right elevational view thereof;

FIG. 7 is a perspective view of the tri-lobe planar heel wound dressing, the foot shown in broken lines are for illustrative purposes only and form no part of the claimed design; and,

FIG. 8 is a perspective view of the tri-lobe planar heel wound dressing.
